UNITED STATES PATENT OFFICE.

GUSTAV ROTHHOLZ, OF BALTIMORE, MARYLAND, AND WILLIAM A. ROTHHOLZ, OF NEW YORK, N. Y.

SPONGING MACHINE.

Application filed November 1, 1927. Serial No. 230,220.

Our invention relates to a new and improved sponging machine.

One of the objects of our invention is to produce a machine which can be used practically continuously so that it will have a large capacity.

Another object of our invention is to provide a sponging machine having heating apparatus such as a steam chest or the like combined with two sets of operating mechanism for moistening and otherwise treating the cloth, so that a web of cloth can be treated, rolled up and allowed to cool, and a second web of cloth can be operated upon while the first web is cooling.

Another object of our invention is to provide a steam cylinder for moistening the cloth, which shall have an improved stuffing box.

Another object of our invention is to provide a machine of simple and efficient construction.

Other objects of our invention will be set forth in the following description and drawings which illustrate a preferred embodiment thereof, it being understood that the above general statement of the objects of our invention is intended merely to generally explain the same and not to limit it in any manner.

Fig. 1 is a side elevation of the improved machine.

Fig. 2 is a detail elevation showing the steam cylinder together with certain of the operating mechanism.

Fig. 3 is a section on the line 3—3 of Fig. 1.

Fig. 4 is a sectional view on the line 4—4 of Fig. 1.

Fig. 5 is a sectional view on the line 5—5 of Fig. 4.

Fig. 6 is a sectional view on the line 6—6 of Fig. 4.

Fig. 7 shows a detail view of the drive.

The web of cloth C may be in the form of a loose pile at the right-hand side of the machine. This web C is then led over the roller 1, under the roller 2 and then over the roller 3. The rollers 1 and 2 are ordinary tension rollers of any suitable and well known type, which aid in keeping the web of cloth taut. The web of cloth is then led over the steam box 4. This steam box 4 is maintained at the proper temperature by means of steam which is caused to circulate

through the same in the ordinary and well known manner so that the cloth is heated to the proper temperature before it is led over the moistening cylinder 5.

As the web of cloth is led around the first moistening cylinder 5, it is joined by the leader cloth C' which is wound up upon the roller 7. This leader cloth C' passes over the roller 8 and then passes underneath the web C, at the underside of the moistening cylinder 5. The roller 7 is provided with any suitable tension device so that the webs C and C' are wound up spirally upon the cylinder 5.

While the first web of cloth C is being treated upon the cylinder 5, in order to steam it or cool it or the like, a second web of cloth C can be led between the rollers 1' and 2' and over the roller 3'. The rollers 1', 2' and 3' correspond in function to the rollers 1, 2 and 3 so that the machine generally consists of two like halves. The second or left-hand web of cloth C can pass over the steam box 4 in a direction reverse to the one previously described and this second web can then be wound upon the cylinder 5', which corresponds in function to the cylinder 5. The second leader cloth is unwound from the roller 7', which corresponds in function to the roller 7.

A motor M of any suitable type is mounted upon a shaft provided with a gear 50 which meshes with the gear 9 mounted upon the shaft 8'. The shaft 8' is provided with a sprocket 10' which is connected by means of the chain 11' to a sprocket upon the driven or secondary shaft 10.

The secondary shaft 10 is provided with a hand wheel 11, and a suitable double-throw clutch of any suitable type (not shown in the drawings) is provided for connecting the secondary shaft 10 to the sprocket 12 which is driven by the chain 11'. The clutch connecting the driven shaft 10 to the sprocket 12 can be of any suitable type so as to permit the operation of the driven shaft 10 at two different speeds, namely, at high speed and at low speed. Since clutches of this type are in themselves old and well known and form no part of our invention, we have omitted the illustration thereof from the drawings, for the sake of clearness. The cylinder 5 is mounted upon a hollow shaft 33 provided with a gear 14 which meshes with a smaller gear 15 upon the driven shaft 10.

10. The gear 14 also meshes with the gear 16 upon the shaft 17, provided with a hand wheel 18.

When the cloth C and leader cloth C' have been wound up upon the cylinder 5, the drive is shifted to the right-hand side of the machine. The operator can then utilize the hand wheel 18 for rapidly stopping the movement of the first cylinder 5.

10 15 20 25 30 35 The intermediate drive gear 15 upon the shaft 10 can be slid longitudinally upon the shaft 10 by means of an ordinary shift lever 20 so that said gear 15 either meshes with an idler gear which meshes with the left-hand gear 14 or with the right-hand gear 21. The gear 15 can be connected to shaft 10 by any well-known connection for the purpose. Thus the shaft 10 may be provided with a key slidably fitting in a slot of the gear 15.

10 15 20 25 30 35 The right-hand gear 21 is mounted upon a shaft 22 provided with a sprocket 23 which is connected by means of a chain 24 to the sprocket 26 of the shaft 27, upon which the second cylinder 5' is located. This shaft 27 is provided with a gear 28 which meshes with a smaller gear 29 upon the shaft 17'. This shaft 17' is provided with a hand wheel 18' which can be utilized by the operator for bringing the second cylinder 5' to a rapid stop, after this has been disconnected from the driven shaft 10.

10 15 20 25 30 35 As shown more particularly in Fig. 2 the cylinder 5 is provided with perforations 30 through which steam can be forced to heat and moisten the cloth. As shown in Fig. 3 this steam can be caused to enter through the pipe 31 at a pressure of about 60 to 80 pounds per square inch from any suitable boiler and the same is then caused to pass through the hollow shaft 33 to the inner perforated cylinder 34, and then out through the perforations 30.

10 15 20 25 30 35 The temperature within the cylinder 5 can be raised and be properly maintained by means of super-heated steam which passes through the coil 35. As shown in Fig. 4, the super-heated steam passes from the boiler before mentioned (not shown in the drawings) through the pipe 36 so that the coil 35 will always maintain the cylinder 5 at the proper temperature, in order to prevent the steam issuing from the perforations 34 from condensing within the cylinder 5.

10 15 20 25 30 35 The steam which passes through the inlet pipe 36 passes through the heating coil 35 and then out through the return pipe 37 into the chamber 38, then into the hollow shaft 33 and out through the lateral outlet pipe 39 by means of a suitable port.

The hollow shaft 33 is mounted in bearings 40 which are connected to the frame F of the machine. One of these bearings is shown in Fig. 4.

10 15 20 25 30 35 In order to prevent any leakage of the

steam passing into the heating coil 35, an improved stuffing box 41 is provided. This stuffing box 41 is provided with the usual gland or follower 42 to compress the packing material. The casing 43 of the stuffing box is provided with a second stuffing box 44 having a gland or follower 45. The glands 42 and 45 are slidably mounted upon their respective adjacent parts and bolts B of any suitable type can be utilized, as shown 75 in Fig. 2, for forcing the glands 42 and 45 inwardly and for holding them stationary while the shaft 33 can freely revolve.

10 15 20 25 30 35 The cloth which is led to the cylinder 5 for example, is first heated to a suitable temperature by being passed over the steam box 4 and it is then led over and wound upon the cylinder 5 while steam is caused to pass out of the cylinder 5 until the said stem passes through the outer layer or winding of the cloth which has been rolled up upon the cylinder 5 by the operation of the machine. The steam supplied through the pipe 31 is then immediately shut off and the interior of the cylinder 5 is then immediately subjected to a vacuum by means of the vacuum pump V which is connected by means of the pipe 32 to the interior of the hollow shaft 33. The vacuum pump V is driven by the motor M which may be an electric motor of any suitable type, by means of the chain 51 which is connected to sprockets on the shaft 8' and the shaft of pump V.

10 15 20 25 30 35 The vacuum utilized may be 10 to 15 inches of mercury. The vacuum pump V is operated for about seven minutes until the cloth which has been wound up upon the cylinder 5 has been cooled and dried.

10 15 20 25 30 35 The roller 7 is then operated in the direction indicated by the arrow in Fig. 1 to rewind the leader cloth thereon, this being done by throwing in a suitable clutch. This movement carries the web C' back over the roller 8. A wind-up roller W is provided for the cooled and dried cloth C and this is provided with bearing pins which rest upon the adjacent frame member F.

10 15 20 25 30 35 The roller 7 is provided with brake or tension members 60 which are operated by the handle 61.

10 15 20 25 30 35 The chain 11² shown in Fig. 1, is for the purpose of providing the low speed drive for the shaft 10. The shaft 50' which operates the roller 7' by means of an intermediate chain drive 52, has its shaft suitably actuated from the shaft 8'. The roller 8² corresponds in function to the roller 8.

10 15 20 25 30 35 The cylinders 5 and 5' are similar in structure and function. Thus, the hollow shaft 27 is similar to the hollow shaft 33 previously mentioned, and it is provided with similar stuffing boxes and the like.

10 15 20 25 30 35 The pipe 32 is suitably connected to the shafts 33 and 27.

The shaft 8' and the shaft of pump V are provided with sprockets connected by a chain 51.

The roller W' corresponds to the roller 5 W. The roller 7' can be connected to its shaft by a suitable clutch (not shown) so that its operation is similar to that of roller 7. Each of these rollers 7' and 7 is free to turn when the leader cloth is being unwound 10 thereof and is connected to its shaft to be positively operated to rewind the leader cloth thereon.

We have shown a preferred embodiment 15 of our invention, but it is clear that numerous changes and omissions could be made without departing from its spirit.

We claim:—

1. A sponging machine comprising a stationary steam chest, perforated cylinders located at opposite sides of said steam chest at fixed distances therefrom, operating mechanism adapted to separately operate said perforated cylinders to wind up thereon a web of cloth which has been led over said 25 steam chest, rolls of leader cloth respectively associated with said perforated cylinders, operating mechanism adapted to separately actuate said rolls, and take-off mechanism for the cloth located at opposite sides of said 30 steam chest, so that a web of cloth can be led in one direction over said steam chest to one of said perforated cylinders, while a roll of cloth wound up on the other cylinder is being treated thereon.

2. In a sponging machine, the combination 35 of a stationary steam chest, perforated cylinders mounted on shafts located on opposite sides of said steam chest at fixed distances therefrom, a driving shaft located on a level lower than the level of said steam 40 chest, a driven shaft connected to said driving shaft, and controllable connecting means adapted to separately connect either of the shafts of said cylinders to said driven shaft.

3. In a sponging machine, the combination 45 of a perforated cylinder, a hollow shaft on which said cylinder is mounted, a steam coil having an inlet pipe mounted in and projecting beyond said hollow shaft, the outlet end of said steam coil being spaced from 50 the inlet pipe and being connected to a chamber forming part of said cylinder and communicating with said hollow shaft, a hollow bearing for said shaft in which said hollow shaft terminates, the space between said 55 hollow shaft and the adjacent inner wall of the bearing being closed by a stuffing box, said hollow bearing having an outlet port for the exhaust steam from said coil, the inlet pipe projecting beyond said hollow shaft and 60 having a second stuffing box located between it and the adjacent inner wall of said hollow bearing.

In testimony whereof we affix our signatures.

GUSTAV ROTHHOLZ.
